BEAM TYPE HYDRAULIC JACK

Robert E. Wooley, Charlotte, N. C., assignor of
one-half to Clifford E. Smythe, Charlotte, N. C.

Application July 7, 1952, Serial No. 297,489

5 Claims. (Cl. 60—52)

1

This invention relates to hydraulic jacks, of the type used in automotive vehicle repair shops and which include a wheeled frame or carriage having a pivoted beam thereon, the frame being provided with handle levers for moving the jack from one place to another and, also, for raising and lowering the beam of the jack. More especially, this invention is concerned with improved means for directing hydraulic fluid under pressure to the lifter cylinder of a jack of the character described for raising the beam and saddle or cap to, in turn, raise an article, such as the axle of an automotive vehicle, resting upon said jack saddle.

Heretofore, beam-type hydraulic jacks have included a housing or reservoir for the hydraulic fluid having valve means for establishing communication between the reservoir and the usual hydraulic-cylinder and wherein a pair of pumps, including plungers working in corresponding sleeves or cylinders, were provided to direct the fluid from the reservoir to the hydraulic cylinder. These plungers have extended through a wall of the reservoir thereby requiring that packing glands of a sort be provided to insure that the fluid would not leak around the plungers. It has been necessary for the plungers to project out of the housing or reservoir in order to facilitate connecting the plungers to the jack operating handle levers and wherein universal joints were interposed in the connections for operating the valve means. This has necessitated periodic replacement of the packing material carried by the packing glands and, if the packing material was not replaced periodically, as is frequently the case, the hydraulic fluid would leak around said plungers and collect on the floor of the plant or shop in which the jack was being used.

It is therefore the primary object of this invention to provide a jack of the type described wherein the pumps and the operating parts therefore are entirely enclosed within the reservoir with connections above the normal level of the fluid contained in the reservoir and extending through the side walls of the reservoir to the lower end of the operating levers or handle levers of the hydraulic jack.

It is another object of this invention to provide a hydraulic jack of the type described with a cam operated pressure release or by-pass valve interposed in the connections between the pumps and the main or lifter cylinder with a return passage-way communicating with the release valve and the reservoir and wherein means are provided to

2

automatically move said cam operated valve from one position to another upon the jack saddle or cap being elevated to a predetermined limit and to thus permit any additional fluid which 5 the operator may attempt to pump from the reservoir to the cylinder to return to the parts of the beam-type hydraulic jack under undue stresses.

It is still another object to this invention to 10 provide a control handle disposed closely adjacent the usual handle on the operating levers of the hydraulic jack, with connections between said control handle and the cam for operating the pressure release valve with resilient means normally holding the valve in a closed position and, upon moving the valve control handle in one direction, the by-pass or pressure release valve will be opened to thereby permit the fluid in the 15 main hydraulic cylinder to return to the reservoir and to thereby lower the beam with the saddle thereon.

Some of the objects of the invention having 20 been stated, other objects will appear as the description proceeds, when taken in connection with the accompanying drawings, in which—

Figure 1 is a side elevation of the improved beam type hydraulic jack showing the beam and saddle in a raised position;

Figure 2 is a top plan view of the structure 25 shown in Figure 1;

Figure 3 is an enlarged view looking at the right hand end of Figure 1, but with the upper portions of the operating levers broken away;

Figure 4 is an enlarged elevation of the lower 30 portion of Figure 3;

Figure 5 is an enlarged fragmentary top plan view taken substantially along the line 5—5 in Figure 1 with parts broken away and other parts being shown in section and also omitting the cover from the reservoir;

Figure 6 is an enlarged vertical sectional view 35 taken substantially along the line 6—6 in Figure 5 showing, particularly, the structure of the valve mechanisms for controlling the flow of hydraulic fluid between the lifter cylinder and the reservoir;

Figure 7 is an enlarged vertical sectional view 40 taken substantially along the line 7—7 in Figure 6 and showing the high speed pump cut-off valve and the high speed pump;

Figure 8 is a vertical sectional view at a reduced scale taken substantially along the line 45 8—8 in Figure 6 and showing the cam operated combination stroke-limiting and manually oper-

able pressure release valve, the structure of the lifter cylinder and the pivotal connection between the frame of the hydraulic jack and the beam;

Figure 9 is a vertical sectional view at a reduced scale taken substantially along the line 9-9 in Figure 6, showing the low speed pump and associated valve means within the reservoir;

Figure 10 is an enlarged fragmentary vertical sectional view, mostly in elevation, taken substantially along the line 10-10 in Figure 2 and showing, particularly, the means for operating the combination stroke-limiting and release valve when the saddle and the corresponding beam have moved upwardly a predetermined distance;

Figure 11 is an enlarged vertical sectional view, mostly in elevation, taken substantially along the line 11-11 in Figure 2 and showing the opposite side of the handle lever from that shown in Figure 10;

Figure 12 is a vertical sectional view at a reduced scale taken substantially along the line 12-12 in Figure 6 and showing, particularly, the overload safety valve;

Figure 13 is an enlarged vertical sectional view taken substantially along the line 13-13 in Figure 10;

Figure 14 is an enlarged vertical sectional view taken substantially along the line 14-14 in Figure 12;

Figure 15 is an enlarged vertical sectional view taken substantially along the line 15-15 in Figure 10.

Referring more specifically to the drawings, the numeral 10 broadly designates the wheeled frame of a hydraulic beam-type jack which pivotally supports a beam assembly broadly designated at 11 and a handle assembly broadly designated at 12. The frame 10 comprises a pair of elongated side frame members or side plates 14 and 15 which are spaced from each other at their front ends by a shaft or axle 16, reduced opposite ends of which slidably penetrate the side plates 14 and 15 and have front wheels 17 and 18 rotatably mounted thereon.

A base plate 20 has its opposite edges suitably secured to the proximal surfaces of the lower medial portions of the side frame members or plates 14 and 15 and spans the distance therebetween (Figures 3, 4, 5, and 8). The lower edges of a pair of transversely based ram guides 21, 21' are suitably secured to the upper surface of the base plate 20 and each has an inwardly projecting rib or flange 22, 22' at the upper edge thereof which extends downwardly and rearwardly at an angle as is clearly shown in Figures 4, 8, and 10 for guiding a ram, to be later described.

Reservoir

Suitable caster wheels 25 and 26 are rotatably mounted in respective brackets 27 and 28 suitably secured to the outer surfaces of the side plates 14 and 15 of the frame 10 adjacent the rear ends thereof. The rear portions of the side plates 14, 15 are held in spaced relation to each other by a plurality of projections 31 (Figure 6) extending outwardly from a hydraulic fluid reservoir 32 having a bottom 33, front and rear walls 34 and 35, respectively, and spaced side walls 36 and 37. The level of the hydraulic fluid in the reservoir 32 is shown by broken lines indicated at L in Figures 7, 8, and 12.

The top of the reservoir is closed by a closure plate 40 and between the closure plate 40 and the

upper edges of the walls 34 to 37, inclusive, is a gasket 41 of any desired material. The closure plate 40 is removably secured to the walls 34 to 37, inclusive, as by screws 42. The reservoir 32 and the various parts contained therein form the most important features of the present invention and will be later described in detail.

It will be observed in Figures 5, 8, 10, and 12 that a lifter or main cylinder 44 is suitably secured to, or integral with, the front wall 34 of the reservoir 32 and extends forwardly and upwardly at slight angle relative to the horizontal and has a hollow lifter position or ram 45 mounted for longitudinal sliding movement therein. The lifter piston is provided with a closure or abutment 46 adjacent the rear end thereof, the front surface of which engages the rear end of a ram rod or pin 47. The cylinder 44 has suitable packing material 48 held therein by an annular gland screw 49 (Figure 8). The piston 45 also has a tubular dust shield 45a integral therewith which slidably engages the exterior surface of the thickened outer portion of the cylinder 44.

The front end of the pin or plunger 47 is fixed 25 intermediate the ends of a transverse guide bar 50, to the lower surface of which a pair of guide bars 51 are suitably secured. The outer surfaces of the guide bars 51 engage the proximal edges of the flange portions 22 of the inverted L-shaped members 21. A transverse guide bar 52 is fixed to 30 the lower surfaces of the blocks 51 and slidably engages the lower surfaces of the flange portions 22.

Beam assembly

35 The beam assembly 11 comprises links 53, 53' pivotally connected to opposite ends of the transverse bar 50. The links 53, 53' extend rearwardly in Figures 5 and 8 and are pivotally mounted between the proximal surfaces of the lower or front corner portions of outer and inner beam levers or bell cranks 54, 55, and 54', 55' respectively, as at 40 56 (Figures 3, 4, 8, and 10). The outer beam levers 54, 54' are substantially triangularly-shaped and the inner beam levers 55, 55' are substantially L-shaped. The lower rear corner portions of the beam levers 54, 55, 54', and 55' in Figure 10, are penetrated by a common transverse tubular member 57, to which they are suitably secured, as by welding. The tubular member 57 is oscillatably mounted on a bushing 63 which serves as a spacer between side plates 14 and 15 and through which a transverse shaft 61 extends. Opposite ends of the tubular member 57 slidably and oscillatably engage the proximal surfaces of 50 the side frame members 14 and 15 and the opposite ends of the shaft 61 penetrate the side walls or frame members 14 and 15 and are fixed therein, by any suitable means such as nuts 62.

55 It will be observed in Figures 3 and 4 that the lower portions of the beam levers 54, 55, 54' and 55' are spaced from each other, but the upper ends of the outer beam levers 54 and 54' converge inwardly and engage the outer surfaces of the respective inner beam levers 55 and 55'. The upper ends of the beam levers 54, 55, 54', 55' are disposed between respective bifurcated portions 63 and 63' of a weight supporting cap or saddle broadly designated at 64 and which further comprises a transverse portion 65 which spans the distance between the bifurcated portions 63 and 63' and is integral therewith. The cap or saddle 64 also includes a substantially circular portion 66 which is cast integral with the portions 63,

It will be observed in Figure 1 that the bifurcated portions 63 and 63' are substantially triangularly-shaped, the upper ends of the beam levers 54, 55, 54', and 55' being pivotally connected to the upper rear corners of the bifurcated portions 63 and 63', as at 67. The upper ends of parallel links 70 and 70' are pivotally connected, as at 71, to the lower front corners of the respective triangularly-shaped bifurcated portions 63 and 63'. The lower portions of the parallel links 70 and 70' extend downwardly between the outer beam levers or bell cranks 54, 54' and the respective side frame numbers 14, and 15 and are pivotally connected, as at 72, to the side frame members or plates 14, and 15. Each of the parallel links 70, and 70' has a forwardly projecting spring anchor portion 73 integral therewith (Figures 3, 4, and 10) to each of which the upper end of a tension spring 74, 74' is connected. Each tension spring 74, 74' extends downwardly and rearwardly at an angle and is connected to a suitable spring anchor 75 projecting inwardly from the proximal surfaces of the respective side frame members or side plates 14, 15.

The tension springs 74, 74' are provided for the well known purpose of returning the saddle 64 and the beam 11 to lowered positions upon the fluid being released from the lifter cylinder 44 in a manner to be later described. In order to assist in maintaining the beam levers or bell cranks 54, 55, 54' and 55' in proper spaced relation to each other and to lend the rigidity thereto, a transverse beam cover plate 76 is provided, opposite edges of which are disposed closely adjacent the proximal surfaces to the side plates or side frame members 14, 15. The beam cover plate 76 is suitably secured to the rear or upper surfaces of the beam levers or bell cranks 54, 55, 54', and 55' by any suitable means such as welding (Figures 1, 2, 3, 5, and 10). The beam cover plate 76 also assists in preventing dirt or foreign matter from collecting on the parts therebeneath.

Handle assembly

It will be observed in Figures 1, 2, 10, and 11 that the hydraulic fluid reservoir 32 is also covered by a removable hood 77, which is shaped to conform to the configuration of the upper and rear edges of the side frame members 14, 15 and is suitably secured thereto, as by screws 80. The hood 77 enhances the appearance of the jack and prevents dirt from accumulating on the parts therebeneath. Opposite side portions of the hood 77 are cut away to form slots 81, 81' through which a pair of operating lever or handle lever extensions 82, 82' loosely extend. The extensions 81 and 81' are parts of the handle assembly 12. The lower ends of the handle lever extensions 82, 82' are bifurcated to form respective slots 83, 83' therethrough.

The upper portions of the handle lever extensions 82, 82' have the lower ends of respective handle operating levers 84, 84' suitably secured therein, as by screws 85. The lower portions of the handle levers or operating levers 84, 84' are held in proper spaced relation by a brace 86 suitably secured thereto. The handle levers 84, 84' converge upwardly and are suitably secured to opposite sides of a handle block 87 having a handle 90 integral therewith.

Referring to Figures 5, 10, 11, and 13, it will be observed that the bifurcated lower ends of the handle levers or operating lever extensions 82

and 82' each has a hub member 91 suitably secured thereto, as by welding, or which hub member may be cast integral therewith. The hubs 91 loosely penetrate the side plates 14, 15 (Figure 13). Each of the hubs 91 is provided with an outer tapered bore 92 and inner straight bore 93. The tapered bores 92 of the hubs 91 are mounted on corresponding tapered portions 94 of a transverse pump operating shaft 95. The pump operating shaft 95 is oscillatably mounted in floating bushings 96, the proximal ends of which are flush with the proximal surfaces of side walls 36, 37 of the reservoir 32. These bushings 96 are loosely mounted in the side walls 36, 37. The straight bores 93 of the hubs 91 are oscillatably mounted on the outer portions of the bushings 96.

The outer ends of the hubs 91 are engaged by washers 101 which are tightened against the hubs 91 by nuts 102 threadably mounted on reduced opposite ends of the transverse pump operating shaft 95. It will be noted that the hubs 91 are keyed, as at 103 (Figure 13), to the corresponding tapered portions 94 of the transverse pump operating shaft 95. A sleeve or tubular member 105 is also fixed on the medial portion of the shaft 95, as by a key 104 and set screws 106. Opposite ends of the sleeve 105 slidably and oscillatably engage the proximal surfaces of the side walls 36 and 37 of the reservoir 32.

It will be observed in Figures 5 and 9 that the sleeve 105 has a pair of longitudinally spaced radially extending arms 107 integral therewith, to the outer end of each of which a pair of links 110 are pivotally connected, as at 111. The links 110 extend downwardly and rearwardly at an angle and are pivotally mounted on a common transverse shaft 112 which slidably penetrates enlarged portions 113 and 114 (Figures 7, 9, and 13) of forwardly and rearwardly extending plungers or piston rods 115 and 116, respectively, which are disposed in parallel spaced relation adjacent the bottom of the reservoir 32. These plungers 115, 116 are parts of respective high speed and low speed ram actuating pumps P-1, P-2.

It will be observed in Figures 5, 7, and 9 that the front portions of the pump piston rods 115, 116 are mounted for longitudinal sliding movement in respective substantially tubular guide members 120 and 121, the rear ends of which are closed and the reduced front ends of which threadably penetrate the rear wall 35 of the reservoir 32. Each of the piston rods 115 and 116 has a longitudinally extending channel or passageway 122 in the rear portion thereof and a transverse passageway or port 123 to permit ingress and egress of air and/or fluid in back of the corresponding piston rods 115 and 116.

The piston rods 115 and 116 are of substantially the same diameter and the front end of the piston rod 115 has a suitable piston 124 and piston cup 124a fixed thereon which are mounted for longitudinal sliding movement in a high speed pump cylinder 125. The cylinder 125 is suitably secured, as by welding, to the rear surface of a valve body 126 shown as an enlarged or thickened transverse portion integral with the front wall 34 of the reservoir 32. It will be noted that the valve body 126 is spaced slightly above the upper surface of the bottom wall 33 of the reservoir 32 to form a passageway 127 therebetween for purposes to be presently described.

A low speed pump cylinder 130 is also suitably

secured to the rear surface of the valve body 126, as by welding. It will be observed in Figure 9 that the front end of the piston rod 116 also serves as a piston and is mounted for longitudinal sliding movement in the low speed pump cylinder 130, the rear portion of the low speed pump cylinder 130 being enlarged and having suitable packing material 132 held therein by a gland screw 133 to thereby prevent the fluid from escaping from the rear end of the low speed pump cylinder 130. It is to be understood, however, that the level L of the hydraulic fluid may be substantially above the level of the cylinders 125 and 130 as shown, if desired. As a matter of fact, the level of the hydraulic fluid in the reservoir 32 may be the same as the lower surface of the tubular member 105, if desired.

Valve mechanisms

The pumps P-1 and P-2 are respectively termed as a high speed pump and a low speed pump, since the high speed pump cylinder 125 has a relatively larger diameter than the low speed pump cylinder and, accordingly, the high speed pump plunger or piston rod 115 is instrumental in raising the saddle 64 at a relatively higher speed with a given number of strokes of the operating levers 84, 84' of the handle assembly 12 than the low speed pump piston rod 116. It is evident that a substantially greater amount of hydraulic fluid is displaced by the piston 124 and the piston cup 124a upon each active stroke thereof than is displaced by the low speed pump piston rod 116 upon each active stroke thereof.

In order to direct hydraulic fluid into the cylinders 125, 130 upon inactive or rearward strokes thereof and to subsequently direct fluid under pressure from the cylinders 125, 130 to the lifter cylinder 44, it will be observed in Figures 7, 8 and 9 that the front wall 34 and the enlarged valve body portion 126 thereof are provided with a horizontal passageway 140 therein which communicates with the interior of the lifter cylinder 44. The valve body 126 also has a pair of horizontal passageways 141, 142 therein which communicate with the respective pump cylinders 125, 130.

The valve body 126 has two sets of three axially aligned vertically extending passageways, chambers, or bores therein one set of which is indicated at 143, 144, and 145 and the other set of which is indicated at 146, 147, and 148 reading from the uppermost to the lowermost bores. The bores 143, 144, and 145 progressively decrease in diameter and the lowermost passageway or bore 145 communicate with the passageway 127 beneath the valve body 126.

The passageways or bores 146, 147, and 148 also progressively decrease in diameter and the lower bore or passageway 148 also communicates with the passageway 127 beneath the valve body 126. The upper ends of the bores 143, 146 are closed by respective threaded plugs 151, 152. The horizontal passageways 141, 142 communicate with the respective intermediate vertically extending passageways or bores 144, 147. The shoulders formed at the junctures of the respective passageways 144, 145, and 147, 148 normally support check balls or valve members 153 and 154, respectively. The shoulders formed by the respective passageways 143, 144, and 146, 147 also support respective check balls or valve members 155 and 156. The check balls 153 and 154 may also be termed as respective high speed pump and low speed pump suction valves and the check balls 155 and 156 may also

be termed as respective high speed pump and low speed pump discharge valves.

It will be observed in Figure 8 that the lifter cylinder passageway 140 is substantially L-shaped and the valve body 126 has a horizontal transverse passageway 160 therein, the medial portion of which communicates with the vertical leg of the substantially L-shaped passageway 140 and opposite ends of the passageway 160 also communicate with the large upper bores or passageways 143, 146 (Figure 6).

Referring to Figure 7, it will be observed that the valve body 126 has a relatively small passageway 162 therein which communicates with the passageway 141 and also communicates with an enlarged passageway or chamber 163 in which a high speed pump pressure release valve 164 is mounted. The lower end of the high speed pump pressure release valve 164 is preferably conically-shaped and is normally urged to close the passageway 162 by a compression spring 165 which surrounds a reduced stem portion of the high speed pressure release valve 164. The upper end of the chamber or passageway 163 is closed by a threaded plug 166 which may be adjusted to vary the pressure of the spring 165.

The valve body 126 is provided with an overflow discharge port or orifice 167 which communicates with the chamber or passageway 163 for a purpose to be later described. The valve body 126 is also provided with a substantially L-shaped passageway 170 (Figure 6), the horizontal leg of which communicates with the intermediate vertical passageway 147 and the vertical leg of which communicates with a vertically extending passageway or overload safety valve chamber 171. A valve seat 172 is formed at the juncture of the passageways 170 and 171 and an overload safety valve, in the form of a check ball 174, is normally urged against the valve seat 172 by a compression spring 175. The lower end of the compression spring 175 engages a disk 176 which bears against the check ball 174 and the upper end of the compression spring 175 engages the lower surface of a threaded plug or screw 177 threadably mounted in the upper end of the chamber or passageway 171. The plug 177 provides for adjustment of the pressure exerted on the ball 174 by the spring 175.

A particularly important feature of the present invention is a unique cam controlled combination automatic stroke limiting and manually operable pressure release valve which serves to release hydraulic fluid from the lifter cylinder 44 and to return the hydraulic fluid to the reservoir 32 when the operator desires to lower the saddle 64 and beam assembly 11. This cam controlled release valve also functions to automatically return hydraulic fluid to the reservoir which may be pumped into the valve body 126 by the high speed pump piston 124 or the low speed pump piston rod 116 when the saddle 64 has been raised to a maximum limit to thereby prevent placing the beam assembly 11 and the associated movable parts under undue stresses.

To this end, the valve body 126 also has a centrally disposed bore or passageway 180 therein (Figures 6 and 8) in which a valve shank 181 is mounted for vertical sliding movement. The valve shank 181 is preferably circular in cross section and has a reduced intermediate portion 182 and a conically-shaped pressure release valve portion 183 on the lower end thereof which, at times, seats against the open upper end of the vertical leg of a substantially L-shaped passage-

way or channel 184. The passageway or channel 184 also communicates with the passageway 140. The pressure release valve 183 is normally urged to opened position by any suitable means such as a compression spring 185 which surrounds the conical valve portion 183 and bears against a shoulder formed at the juncture of the intermediate portion 182 and the conical valve portion 183. The valve body 126 has a fluid discharge port or orifice 186 therein which communicates with bore 180 at a point below the juncture of the shank 181 and the intermediate portion 182 thereof.

The pressure release valve 183 is normally held in lowered or closed position as in Figures 6, 8, and 12 by an abutment 187 shown in the form of an adjustment screw which slidably penetrates the front end of a lever 190 and bears against the upper end of the shank 181. The lever 190 is oscillatably mounted intermediate its ends, as at 191, between the upper ends of a pair of ears 192 which extend downwardly and are formed integral with valve body 126. A roller or cam follower 193 is mounted in the bifurcated rear end of the lever 190 and bears against an eccentric or cam 194 keyed or otherwise fixed on a transverse cam shaft 195, one of which is oscillatably mounted in a bushing 196 (Figure 14) fixed in a boss portion 197 projecting inwardly from the side wall 15.

The shaft 195 is also oscillatably mounted in a bushing 200 suitably secured, as by a pressed fit in a shouldered tubular bearing member 201 which threadably penetrates the side wall 14 of the reservoir 32. The right-hand end of the shaft 195, in Figure 14, bears against the wall 15 and the shaft 195 is prevented from moving to the left, in Figure 14, by a collar 202 adjustably secured on the shaft 195 and bearing against the inner surfaces of the bushing 200 and the bearing member 201.

The bushing 200 has a circular groove 203 in the inner wall thereof in which an O ring 204 is disposed to thereby prevent hydraulic fluid from leaking around the shaft 195. The shaft 195 and the cam 194 are normally urged in a clockwise direction, in Figures 8 and 12, by any suitable means such as a torsion spring 205 which surrounds the right-hand portion of the cam shaft 195 (Figure 14). One end of the spring 205 is connected to the boss portion 197 of the side wall 15 and its other end is connected to a collar 206 adjustably secured on the shaft 195.

The left-hand end of the cam shaft 195 (Figure 14) has one end of a crank arm 210 fixed thereon which extends forwardly and has a follower or roller 211 mounted thereon which is normally urged into engagement with the outer surface of a substantially U-shaped or horse-shoe-shaped cam element or lever 213. The U-shaped cam element is disposed within the slot 83, as in the lower end of the handle lever or operating lever extension 82 shown in Figures 10, 11, and 13. The lower end of the cam element 213 is pivotally mounted, as at 214, on the operating lever extension 82 and curves upwardly in a semi-circular manner and partially circumscribes the corresponding hub 91.

The upper or free end of the cam element 213 is engaged by a roller or follower 215 mounted in the upper end of a cam operating lever 216. The cam operating lever 216 is also oscillatably mounted intermediate its ends, as at 217, in the slot 83 in the lower portion of the operating lever extension 82. It will be most clearly observed in Figure 11 that one of the side walls defining

the slot 83 in the operating lever extension 82 has an arcuate slot 220 therein, through which a pivot pin 221 carried by the cam operating lever 216 loosely extends.

5 The lower end of a link 223 is pivotally mounted on the pivot pin 221 (Figures 5 and 11) and extends upwardly adjacent the inner surface of, and in parallel relation to, the handle lever 84. The upper end of the handle lever 84 of the 10 handle assembly 12 has a slot 224 therein (Figure 1) and the block 87 has a groove or cavity 224a therein (Figure 2) which coincides with the slot 224. A beam or saddle lowering handle or beam release lever 225 projects through the slot 224 and into the cavity 224a in the block 87 and is pivotally mounted therein, as at 230.

The upper end of the link 223 is pivotally connected intermediate the ends of the beam or saddle release lever 225, hence, the lever 225 is normally urged forwardly or away from the jack handle 90 by the torsion spring 205 heretofore described (Figure 14).

Referring again to Figures 10 and 11, it will be observed that the crank arm 210 has one end 25 of a link 231 pivotally connected thereto. The link 231 is shown in the form of a link chain in Figures 10 and 11 and extends forwardly and is pivotally connected to the beam lever or bell crank 54, as at 232 (Figure 10), by means of a clevis 233 threadably embedded in a connecting link member 234 to which one end of the link chain is pivotally connected. This clevis 233 is provided to facilitate accurate adjustment of the link 231 so that, when the saddle approaches the 30 limit of its upward movement, substantially as shown in Figure 1, the link chain forming the link 231 will then become taut and will move the crank arm 210 and shaft cam 195 in a counter-clockwise direction in Figure 10, whereupon the 35 cam 194 will move from the solid line position to the broken line position shown in Figure 8 thereby permitting pressure release valve 183 to move upwardly under impetus of the compression spring 185. It is evident that this will cause 40 any fluid directed under pressure to the passageway 140 (Figures 6 and 8) to merely return to the reservoir through the passageways 184, 180 and 186 successively.

Method of operation

50 Assuming the beam assembly 11 to be in the horizontal or lowered position shown in Figure 8, the further assuming that the beam pressure release lever 225 is in its normal position, the cam or eccentric 194 is then in the solid line position shown in Figure 8 and the pressure release valve 183 is also in the closed position shown in Figure 8. The operator then positions the saddle 64 beneath the articles to be raised thereby whereupon the handle lever assembly 12 is manually oscillated to, in turn, oscillate the shaft 95.

55 It is evident that oscillation of the shaft 95 causes the tubular member or sleeve 105, the arms 107, the links 110, the transverse pivot shaft 112, and the pump piston rods 115 and 116 to reciprocate. Now, during the time that the saddle 64 is elevated from its lowermost position until it engages a load, the high speed pump piston 124 performs the work of forcing fluid from the reservoir to the main or lifter cylinder 44 since the pressure of the spring 165 (Figure 7) is such that the high speed pump pressure release valve or cut-out valve 164 will remain seated until pressure of the fluid passing through

11

the passageways 141, as caused by the piston 124, is sufficient to unseat the valve member 164, in which instance, the excess fluid displaced by the piston 124 will flow through the passageways 162 and 163, successively, and will be discharged through the port 167 back into the reservoir 32.

However, until the load carried by the beam assembly 11 is increased up to a predetermined point, upon each active or forward stroke of the piston rods 115 and 116, fluid is forced through the respective passageways 141 and 142 into the respective intermediate chambers or passageways 145 and 147.

Of course, upon each inactive stroke of the piston rods 115 and 116, the valve members or check balls 153 and 154 will be forced upwardly and unseated, due to the suction caused by the piston 124 and the piston rod 116, and will thereby permit fluid to flow from the reservoir 32, through the passageway 127 beneath the valve body 126, through passageways 148 and 149 (Figure 6) and the respective passageways 144, 141 and 147, 142, into the respective cylinders 125, 130.

As the piston 124 and piston cup 124a move in an active stroke toward the valve body 126, the amount of fluid displaced thereby is substantially greater than the amount of fluid displaced by the relatively smaller piston rod 116 and, therefore, the ball 155 will be unseated, by the force of the fluid flowing into the intermediate chamber or passageway 144, and will thereby permit fluid to flow into the passageway or bore 143 and then through the passageways 160 and 161, successively, to the main or lifter cylinder 44. Thus, the high speed pump P-1 causes the beam assembly 11 and the saddle 64 thereon to move upwardly at a relatively fast rate in the course of each active stroke of the piston rods 115 and 116.

If the low speed pump P-2 was not provided, it is evident that the force required, on the handle 90 by the operator, would be increased considerably upon the saddle engaging and lifting a relatively heavy article. However, as heretofore stated, upon the fluid flowing through the passageway 141 approaching a predetermined pressure, the cut-out valve 164 is unseated thereby permitting excess fluid to flow back into the reservoir 32. When this occurs the relatively smaller amount of fluid forced through the passageway 142 upon each active stroke of the low speed pump piston rod 116 causes the ball 156 to move upwardly or to become unseated while the ball 155 in Figures 6 and 7 remains seated. Fluid under pressure then flows through the passageways 142, 147, 146, 160 and 140, successively, into the lifter cylinder 44 to thus lift the load carried by the saddle 64.

In order that the beam assembly 11 and intervening parts connected to the lifter cylinder 44 are not placed under undue stresses due to overloading the saddle 64 of the lifter piston 45, when the pressure of the fluid in cylinder 44 becomes greater than the pressure of spring 175 against the safety valve 172, the latter is unseated (Figures 6 and 12). Thus, the fluid above over-load balls 155 and 156 causes the same to remain seated although further active strokes are imparted to the high speed pump piston 124 and cup 124a and the low speed pump piston rod 116. Of course, the threaded plug 177 is adjusted to cause the compression spring 175 in Figure 5 to exert a predetermined pressure on the over-load safety valve 172 and, upon this pressure being exceeded by the fluid in the cylinder 44 and

in the passageways 160 and 146 (Figures 6 and 9) the check wall or overload safety valve 172 is then unseated with succeeding active strokes of the low speed pump piston 116. In this event, fluid flows through the passageways 147, 170 and 171, successively, and is then discharged through the orifice 178 (Figure 12).

It has already been described how the link 231 (Figures 10 and 11) will permit the combination stroke limiting valve and manually operable pressure release valve 183 to move upwardly in Figure 8 when the beam assembly 11 has reached its optimum raised position, to thus permit any further fluid pumped into the passageway 140, by either the high speed pump piston 115 or the low speed pump piston 116, to return to the reservoir 32 through the orifice 186 in Figure 8.

Now, when the operator desires to lower the saddle, and, of course, the beam assembly 11, it is merely necessary for the operator to grasp the control handle or lever 225 and move the same toward the jack handle 90. This causes the link 223 to move downwardly thereby moving the levers 213 and 216 in a clockwise direction in Figure 10 and in a counter-clockwise direction in Figure 11. Thus, the cam shaft 195 and its crank arm 210 move in a counter-clockwise direction in Figures 8, 10 and 12, whereupon the pressure of the fluid in the passageways 140 and 184, caused by the load on the lifter piston 45, will unseat the combination stroke limiting and pressure release valve 183 thereby permitting the saddle and the beam assembly 11 to move downwardly as the lifter piston 45 recedes into the lifter cylinder 44, since the fluid then flows from the cylinder 44, through the passageways 148, 184 and 180, successively, and passes back into the reservoir 32 through the orifice 186. It is evident that the tension springs 74 also assist in lowering the beam assembly 11 when the valve 183 is unseated.

It is thus seen that there is provided an enclosed valve assembly and pump unit, which enclosure also serves as the reservoir for the hydraulic fluid thereby insuring that the hydraulic fluid will not leak from within the reservoir 32. This obviates the necessity of providing connections to the high speed pump piston rod 115 and the low speed pump piston rod 116 which are disposed exteriorly of the reservoir 32, such as universal joints or gears, as have heretofore been required. Of course, this also obviates the necessity of providing packing glands and packing material at the points at which the piston rods 115 and 116 have heretofore passed through walls or a wall of the reservoir of the type heretofore employed.

As heretofore stated, the manually operable means for controlling the combination stroke limiting and pressure release valve 183 is one of the primary features of the present invention in that such means is simply constructed in such a manner that it will operate efficiently over a relatively long period without need of repair and is readily controlled by the operator without necessity of the operator removing his hands from the jack handle 90.

In the drawings and specification there has been set forth a preferred embodiment of the invention and, although specific terms are employed, they are used in a generic and descriptive sense only and not for purposes of limitation, the scope of the invention being defined in the claims.

I claim:

1. An improved hydraulic actuating means including a fluid reservoir having a valve mecha-

nism in one end thereof, a pump cylinder projecting inwardly from said valve mechanism, a plunger movable longitudinally in said pump cylinder, guide means spaced from the pump cylinder for supporting said plunger, a rocker shaft journaled in the reservoir above the plunger, a hand lever fixed on the rocker shaft exteriorly of the reservoir for imparting movement to the rocker shaft, a crank fixed on the rocker shaft, a link pivotally connected at one end to said crank and pivotally connected at its other end to a portion of said plunger between the pump cylinder and the guide means, a lifter cylinder extending outwardly from the reservoir and communicating with said valve mechanism and having an annular packing material in its outer end, said valve mechanism having means responsive to movement of said plunger for directing fluid under pressure from the reservoir into said lifter cylinder, a lifter piston longitudinally movable in said lifter cylinder, an annular flange on the outer end of said lifter piston, a tubular dust shield carried by the annular flange and surrounding said lifter piston, said dust shield slidably engaging the exterior surface of said lifter cylinder, a pressure release valve interposed in said valve mechanism, a transverses cam shaft journaled in the reservoir and disposed adjacent the pressure release valve, a cam fixed on the cam shaft, spring means normally urging the cam in one direction to maintain the pressure release valve in closed position, a U-shaped cam element pivoted on said hand lever adjacent said cam shaft, a cam lever pivoted on said hand lever and having one of its ends engaging the free end of the U-shaped cam element, a link connected to the other end of said cam lever, a valve control handle pivotally supported by said hand lever and to which the other end of said link is pivotally connected, and a crank arm fixed to one end of said cam shaft exteriorly of said reservoir and having a follower thereon normally biased against the U-shaped cam element by said spring means.

2. In a hydraulic pump apparatus for actuating a lifter element, a pump having a reservoir provided with side walls and front and rear walls, a lifter cylinder carried by said front wall, a lifter piston connected to the lifter element and being mounted for longitudinal movement in said lifter cylinder, a valve body carried by the front wall of said reservoir, a pump cylinder fixed to the valve body, a pump piston longitudinally movable in said pump cylinder, guide means for said piston spaced from said pump cylinder, a rocker shaft journaled in said side walls of said reservoir, a hand lever fixed to said shaft exteriorly of the reservoir, a first valve means in the valve body for drawing fluid into the pump cylinder upon each inactive stroke of the pump piston, a second valve means disposed in the valve body for directing fluid from the pump cylinder to the lifter cylinder on each active stroke of the pump piston, a pressure release valve movably mounted in said body and said valve body having a passageway communicating with the interior of the lifter cylinder and also communicating with the pressure release valve; the combination of a crank fixed on said rocker shaft within said reservoir, a first link pivotally connected at one end to a medial portion of said pump piston at a point between the pump cylinder and said guide means and pivotally connected at its other end to said crank, cam means including a cam shaft journaled in the side walls

of said reservoir, an eccentric cam fixed on said cam shaft, a valve lever pivotally supported by said valve body, means on one end of the valve lever engaging said cam and means on the other end of said valve lever engaging said pressure release valve, spring means normally urging the cam in one direction to maintain the pressure release valve in closed position, a substantially U-shaped cam element pivotally supported by said hand lever, a cam lever oscillatably mounted on said hand lever and having one of its ends engaging the free end of said U-shaped cam element, a link connected to the other end of said hand lever and extending in parallel relation thereto, a valve control handle pivotally supported by said hand lever and to which the other end of said link is pivotally connected, a second crank fixed to one end of said cam shaft exteriorly of said reservoir and having a follower thereon normally biased in engagement with said U-shaped cam element by said spring means, and a normally relaxed pliable second link connected at one end thereof to said second crank and being connected at its other end to the lifter element whereby, upon said lifter element being raised a given distance, the pliable link will be pulled taut to move the follower on the second crank out of engagement with said U-shaped cam element to move the cam on the cam shaft in the opposite direction from that in which it is biased by said spring means to release said pressure release valve and thereby to release fluid from within the lifter cylinder and, also, whereby movement of the valve control handle will move the U-shaped cam element against the cam lever to also release the pressure release valve.

3. In a fluid pressure pump for controlling the position of a ram, said pump having a fluid reservoir and first valve means connecting said reservoir with said ram for directing fluid from the reservoir to the ram with operation of said pump, said pump also including a longitudinally reciprocable fluid pressure transmitting plunger mounted for longitudinal movement in said reservoir and being supported for longitudinal movement at at least two spaced points in said reservoir, a rocker shaft disposed above the level of said plunger and being journaled in said reservoir, a crank fixed on said rocker shaft, and a hand lever fixed to said rocker shaft exteriorly of said reservoir; the combination of a first link pivotally connected at one end thereof to said crank and being pivotally connected at its other end to said plunger at a point between the spaced means supporting said plunger, a pressure release valve interposed between the ram and the reservoir, a cam adjacent said pressure release valve, a cam shaft journaled in said reservoir and on which said cam is fixedly mounted, spring means normally urging the cam in one direction to maintain the pressure release valve in closed position, a substantially U-shaped cam element pivotally supported at one end thereof on said hand lever, a cam lever pivoted on said hand lever and having one of its ends engaging the free end of the substantially U-shaped cam element opposite from the end thereof which is pivotally connected to the hand lever, a second link connected to the end of said cam lever opposite from the end thereof which engages the U-shaped cam element and extending in substantially parallel relation to said hand lever, a valve control handle pivotally supported by said hand lever at a point remote from the rocker shaft and to which the end of said second link

15

remote from the cam lever is pivotally connected, and a crank arm fixed to one end of said cam shaft exteriorly of said reservoir and having a follower thereon normally biased in engagement with the curved portion of said U-shaped cam element by said spring means whereby movement of the valve control handle will permit said spring means to move the cam lever, the U-shaped cam element and the crank arm to release the pressure release valve for releasing the fluid from the ram.

4. In a structure according to claim 3, a pliable link connected at one end thereof to said last-named crank arm and being connected at its other end to the ram whereby, upon said ram being moved a predetermined distance the pliable link will be pulled taut thereby and move the crank arm out of engagement with the U-shaped cam element to thereby move the cam on the cam shaft in the opposite direction from that in which it is normally urged by the spring means to release said pressure release valve for releasing fluid from said ram.

5. In a fluid pressure pump for controlling the position of a ram, said pump having a fluid reservoir and first valve means connecting said reservoir with said ram for directing fluid from the reservoir to the ram with operation of said pump, said pump also including a hand lever for operating said pump and disposed exteriorly of said reservoir; the combination of a pressure release valve interposed between the ram and the reservoir, a cam adjacent said pressure release valve, a cam shaft journaled in said reservoir and on which said cam is fixedly mounted, spring means normally urging the cam in one direction to maintain the pressure release valve in closed
